RAILWAY TRUCK PEDESTAL STRUCTURE

Ernest F. Dohe and William J. Wilson,
Omaha, Nebr.

Application September 8, 1941, Serial No. 409,948

9 Claims. (Cl. 105—225)

The invention relates to railway rolling stock and more particularly to truck pedestal and axle box assembly and consists in a novel mounting of the liner or journal box lateral motion device on the pedestal.

Because of the increased high speeds at which trains are being run, it has been found that to maintain a good riding truck the fits between the parts of the trucks which have movement relative to each other, such as axle boxes and the frame pedestals receiving the same, should be made as close as possible. It is desirable to have only a small amount of lateral and longitudinal play or clearance between the pedestal legs and the journal box so as to reduce as much as possible the effects of longitudinal and transverse shocks between the box and truck frame. It is also necessary that play between these parts shall not be increased excessively because of wear between the journal box and pedestal legs.

Efforts to obtain the desired results indicated above have been made by providing renewable liners on the pedestal legs and on the journal boxes so that a relatively hard material can be used which will keep the wear to a minimum and so that when wear does take place the liners may be renewed without replacing the frame or journal box parts.

The main object of the present invention is to provide a close fit between the pedestal and the box which will accommodate the necessary movement between the pedestal and the box vertically and transversely of the truck and at the same time avoid undue play or clearance longitudinally of the truck and preferably which includes a liner, or lateral motion device, and provides for the adjustable mounting of the liner on the pedestal to secure the desired result.

This and other detailed objects of the invention as will appear hereafter are attained by the structure illustrated in the accompanying drawing in which—

Figure 1 is a side view of one end of a railway truck with a portion of one wall of the journal box and associated structure sectioned to more clearly illustrate the construction.

Figure 2 is a horizontal section taken approximately on the line 2—2 of Figure 1 and drawn to an enlarged scale.

The truck wheel 1 is mounted on the truck axle 2 which carries the journal box 3 provided with lateral wings 4 which support coil springs 5 on which rests the truck frame 6 including a pedestal jaw 7 for receiving the journal box 55

between the pedestal legs 8. Movement of the box longitudinally of the frame is resisted by anchor rods 9 extending longitudinally of the box with their ends connected respectively to brackets 10 on the box and brackets 11 on the frame.

This arrangement is disclosed and claimed in an application filed by James C. Travilla, Jr. and Otto Jabelmann June 26, 1941, Serial No. 399,838 and in itself does not constitute the present invention.

Each pedestal leg includes a transverse box opposing wall 12 and front and rear side walls 13 and 14 respectively. The adjacent portions 15 of the journal box comprise a side wall 15, paralleling the leg wall 12, and front and rear flanges 16 and 17, paralleling the leg walls 13 and 14.

A liner and lateral motion unit is mounted on 20 the pedestal leg and slidably engages the journal box. This unit includes a U-shaped inner plate member 18 having a transverse portion 19 with flanges 20 extending therefrom alongside of leg walls 13 and 14. A pad 21 of rubber-like material has one face bonded or otherwise secured to portion 19, and its edges terminate substantially flush with the outer faces of flanges 20.

An outer plate member 22 is bonded or otherwise secured to the outer face of pad 21 and 30 preferably is of U section with its flanges 23 parallel but spaced from flanges 20. Member 22 clears the box side wall and has a sliding fit with the box flanges 17 or with flanges 25 of a suitable wear plate 24 provided on the box.

35 This liner unit comprises a lateral motion device as disclosed in Patent No. 2,229,429, issued January 21, 1941, to James C. Travilla, Jr. It accommodates relative movement of the box and pedestal vertically of the truck, although 40 such movement may be yieldingly resisted by anchor rods 9, but resists relative lateral movement between the journal box and pedestal, although yielding to forces tending to produce such relative transverse movement as are encountered when the vehicle enters a curve, when the resulting shocks will be cushioned by the shear resistance of pad 21, and such shocks will be largely dissipated before reaching the truck frame and the car body.

50 The liner unit is held to the pedestal leg by a bolt-like device which includes a shank 26 extending through walls 13, 14 and flanges 20 and retainer plates 27 welded thereon, there being nuts 28 threaded on the end portion of shank 26 and having conical bases fitting the openings in

the retainer plates. To adapt the mounting of the liner unit on the pedestal leg so that proper adjustment can be made between them, to avoid undue play between the journal boxes and the pedestal, and to render the holding device effective, the openings 29 in flanges 20 are enlarged to accommodate initial movement of the liner unit transversely of wall 12 to the correct position for engagement with box 3 in accordance with the centering of the latter in the pedestal, as determined, for example, by anchor rods 9.

In mounting the liner unit and lateral motion device on the pedestal, it is first applied over the pedestal leg and temporarily clamped thereon. Then element 26 is inserted and retainers 27 placed over the ends of element 26 and nuts 28 applied to the ends of element 26 and screwed down to lightly thrust retainers 27 against flanges 20.

If desired, a selective shim 30 of requisite thickness, or more than one such shim, may be placed between wall 12 and plate 19 to adjust the clearance between the box side wall and plate 22 and to provide a firm backing for plate 19. After the proper distance between the liners at opposite sides of the pedestal has been obtained, nuts 28 are tightened and retainers 27 are permanently secured to flanges 20 as by one or more welds W or a continuous weld, applied in situ. The openings in walls 13 and 14 for element 26 snugly seat the latter so that the liner will not shift from desired position after the assembly is completed.

This arrangement makes it possible to effect readily a desired adjustment of the liner, or lateral motion device, and the pedestal and to closely control the fit between the journal box and pedestal. Full annular bearings are provided between element 26, through nuts 28, and the liner unit and the pedestal walls. Hence repeated thrusts between the box and pedestal are unlikely to affect the mounting as would occur if the tapered portions of the nuts had only a line contact with the counter-sunk surfaces in plate 27 or if the bolt shank 26 had only a line contact with the openings in pedestal walls 13 and 14.

The liner unit illustrated and described embodies a lateral motion device and in the appended claims the term liner is intended to cover a lateral motion device of the type described, but it will be understood that a simple liner plate, corresponding to element 18 but directly contacting the box wall and flanges, or wear plates thereon, may be mounted upon the pedestal in the same manner.

Other variations in the details of the construction may be made without departing from the spirit of the invention, and the exclusive use of such modifications as come within the scope of the claims is contemplated.

What is claimed is:

1. In combination, a railway truck pedestal leg, a liner therefor having a journal box opposing portion and a flange extending from said portion over the side of the pedestal leg, a holding device extending through the pedestal leg and said flange, the opening in the pedestal leg providing a snug fit for said device, and the opening in said flange for said device being enlarged to accommodate movement of said liner portion towards and away from the pedestal leg, a member overlying said opening in said flange and the adjacent portion of said flange and apertured to closely fit said device, and separate means fixedly securing said member to said liner flange to pre-

vent movement of said flange relative to said member, device and pedestal leg.

2. A structure as described in claim 1 in which the means securing the member to the liner flange comprises welds applied to the member and the liner flange on a part of the latter facing exteriorly of the pedestal leg.

3. In combination, a railway truck pedestal leg, a liner therefor having a journal box opposing portion and a flange extending from said portion over the side of the pedestal leg, a holding device extending through the pedestal leg and said flange, the opening in the pedestal leg providing a snug fit for said device, and the opening in said flange for said device being enlarged to accommodate movement of said liner portion towards and away from the pedestal leg, a member overlying said opening in said flange and the adjacent portion of said flange and apertured to closely fit said device, and means applicable to said member and liner flange, after adjustment of said liner on said pedestal, for securing said member and flange relative to each other and thereby maintaining the position of the liner on the pedestal.

4. In combination, a railway truck pedestal leg, a liner therefor having a journal box opposing portion and a flange extending from said portion over the side of the pedestal leg, a holding device extending through the pedestal leg and said flange, the opening in said flange for said device being enlarged to accommodate movement of said liner portion towards and away from the pedestal leg, a vertically elongated plate overlying a substantial portion of said flange and apertured to receive and closely fit said holding device to afford an annular bearing for the latter, and means securing said plate to said flange at vertically spaced points near the top and bottom of the flange and plate and intermediate said points to distribute the thrust between said device and flange over an extended area.

5. In combination, a railway truck pedestal for receiving a relatively movable axle journal box and including a leg having front and rear walls and a transverse wall between them arranged to oppose a side of a journal box, a pedestal liner applied to said leg and including a portion extending across said wall and having flanges extending alongside the front and rear walls of the pedestal, a selective shim between said liner portion and the transverse wall of the pedestal leg, a bolt-like device extending through apertures in said pedestal front and rear walls, and through said flanges, and snugly seated in said wall apertures, the apertures in said flanges being enlarged to accommodate adjustment of said liner on said pedestal leg as required for shims of different thickness between the liner and the pedestal leg transverse wall, retainer plates overlying the apertured parts of said flanges and provided with openings, the bolt-like device comprising a shank with tapered units at its ends adjustable relative to each other transversely of the pedestal and fitting in said retainer plate openings, said retainer plates being welded in situ to said liner flanges.

6. In combination, a railway truck pedestal leg, a liner therefor having a journal box opposing portion and flanges extending from said portion over the sides of the pedestal leg, a holding device having an elongated shank extending through the pedestal leg and said flanges, the openings in said flanges for said device being

enlarged to accommodate movement of said liner portion towards and away from the pedestal leg, members overlying said openings and the adjacent portion of said flanges and having apertures to receive said device shank, tapered units on said device shank adjustable relative to each other transversely of the pedestal to snugly fit said member apertures, and separate means fixedly securing said members to said liner flanges to prevent movement of said flanges relative to said members, device and pedestal leg.

7. In combination, a railway truck pedestal leg, a liner therefor having a journal box opposing portion and a flange extending from said portion over the side of the pedestal leg, a plurality of holding devices extending through the pedestal leg and said flange and spaced apart vertically, the openings in said flange for said devices being enlarged to accommodate movement of said liner portion towards and away from the pedestal leg, a member securely engaging a plurality of the devices, and means securing said member to said flange at vertically spaced points to hold said devices and flange against relative movement and to distribute the thrust between said devices and flange over an extended area of said flange.

8. In combination, a railway truck pedestal leg, a liner therefor having a journal box opposing portion and flanges extending from said portion over the sides of the pedestal leg, a plurality of bolts extending transversely through the pedestal leg and snugly fitting therein and also ex-

tending through said flanges, the openings in said flanges for said bolts being enlarged to provide for movement of said liner portion towards and away from the pedestal leg, a plate washer member overlying each flange and apertured for the corresponding ends of said bolts and fitting the same snugly, and means securing each of said plates to the corresponding flange at spaced points following adjustment of the liner and pedestal leg and distributing the thrust between the bolts and the liner over an extended area of the liner.

9. In combination, a railway truck pedestal leg with front and rear walls, a liner therefor having a journal box opposing portion and flanges extending from said portion over the sides of the pedestal leg, said leg and flanges having apertures, a holding device extending through said apertures, and snugly seated in said wall apertures, the apertures in said flanges being enlarged to accommodate the adjustment of said liner on said pedestal leg, retainer plates overlying the apertured parts of said flanges and provided with tapered openings, said holding device being provided with tapered units thereon adjustable relative to each other transversely of the pedestal and snugly fitting the tapered openings in said retainer plates, and means fixedly securing said retainer plates to said liner flanges to prevent movement of said flanges relative to said plates, devices, and pedestal leg.
